UNITED STATES PATENT OFFICE

153,839

DESIGN FOR A KEY CHAIN

Paul Stephen Zahora, Bloomington, Ind.

Application October 22, 1947, Serial No. 142,086

Term of patent 3½ years

(Cl. D17—14)

To all whom it may concern:

Be it known that I, Paul Stephen Zahora, a citizen of the United States, residing at Bloomington, in the county of Monroe and State of Indiana, have invented a new, original, and ornamental Design for Key Chain, of which the following is a specification, reference being had to the accompanying drawing forming a part thereof.

Fig. 1 is a front elevational view of a key chain, the broken portion indicating indeterminate length, showing the essential features of my new design in full lines;

Fig. 2 is a transverse sectional view taken substantially on the line 2—2 of Fig. 1, looking in the direction indicated by the arrows, and drawn to an enlarged scale; and

Fig. 3 is a side elevational view, looking from

the right of Fig. 1 and showing the uppermost fragment of the key chain embodying my new design.

I claim:

The ornamental design for a key chain, as shown and described.

PAUL STEPHEN ZAHORA.
